PACKAGE BINDING MACHINES

Peter Roy Cook, Beckenham, Kent, England, assignor to
Package Sealing Company (Export) Limited, Ealing,
London, a company of Great Britain
Filed Nov. 13, 1962, Ser. No. 236,881
12 Claims. (Cl. 100—4)

This invention is concerned with machines for binding packages with flexible metal binding material and of the kind comprising means for feeding the material endwise, a guide which receives the material and directs it to form a loop with overlapping ends, means for tightening the loop around a package, and a connecting device for joining the ends of the tightened loop.

Moreover, the invention is concerned with a machine of the above kind in which at least some of the machine's components are powered or controlled by pneumatic means which operate in an automatic sequence including the loop-forming operation. This raises the problem of sensing when the free end of the material reaches or approaches its final position during the loop-forming operation, so that the automatic sequence can be stopped or continued.

According to the present invention the machine comprises a controlling air circuit which includes an air duct leading to a bleed port, the arrangement being such that as the free end of the material approaches its final position during the loop-forming operation it effects a change in flow conditions at the bleed port, and the machine also comprises means responsive to the ensuing pressure change in the air duct for at least terminating the feeding action of the feed means.

The pressure change in the air duct may be a pressure rise or a pressure drop, according to whether the bleed port is opened or closed by the free end of the material.

The bleed port may be controlled by its own obturator which is positioned so as to be operated by the free end of the material as the latter approaches its final position. Movement of the obturator in response to actuation by the free end of the material may either open or close the bleed port.

Preferably, the bleed port is normally open and is closed by the free end of the material which itself acts as the obturator. One way of achieving this result is to provide a guide structure which contains the bleed port and which receives the free end of the material as the latter approaches its final position.

The guide structure preferably consists of two parts one of which is movable to open and close it, and the meeting faces of the two parts are formed with confronting grooves one of which, when the guide structure is closed, conducts the material into the aforesaid guide and the other of which contains the bleed port and receives the free end of the material as the latter approaches its final position.

Preferably the connecting device is a twister pinion and the binding material is flattened wire and in this case the guide structure consists of a stationary upper part formed with the groove containing the bleed port and a movable lower part formed with the other groove. The guide structure is preferably opened and closed by an air cylinder and means are provided in the air circuit for causing this air cylinder to open the guide structure at the end of the twisting action of the twister pinion and for closing it after the ejection of the tie.

The feeding means preferably comprises a driving roller, a bodily movable pressure roller and an air cylinder controlled by a pressure-responsive valve for bringing the pressure roller into wire-feeding relationship with the driving roller.

An embodiment of the invention will now be described

2

by way of example with reference to the accompanying drawings in which:

FIGURE 1 is a front view of the machine;
FIGURE 2 is a section in the binding plane;
FIGURE 3 is an enlargement of a part of FIGURE 2;
FIGURE 4 is a diagram of the air circuit;
FIGURE 5 is a section on the line 5—5 of FIG. 1;
FIGURE 6 is a similar section showing the guide ring in the open position;

FIGURES 7 and 8 show a plan of a modified construction which includes an obturator;

FIGURES 9 and 10 show a plan of a further construction which includes an obturator for obtaining a pressure drop instead of a pressure rise.

15 The machine comprises a foundation plate 10 on which the chief working components of the machine are mounted. These components are, a guide ring 11, which surrounds an aperture 12 in the foundation plate, a twister pinion gear box 13, a reversible feed 14 and an extra-tension device 15. Other components are, a supply reel 17, which carries a coil of flattened wire and a slack take-up device 18.

The guide ring has a wire-guiding groove 11a in the surface next to the foundation plate. The guide ring is 25 closed and opened, that is to say moved into and out of contact with the foundation plate, by four air cylinders A which are fixed to the back of the foundation plate. The piston rods 19a of these air cylinders pass through holes in the foundation plate and are connected to lugs 30 19 on the guide ring.

The reversible feed 14 comprises two driving rollers 25 and 67 on two shafts which are geared together and mounted on a pivoted plate 68. One of the shafts is driven continuously through a friction clutch, by an electric motor 16. Above the driving rollers are two pressure rollers 70 and 71 which are mounted in a tiltable holder 72. The holder is tilted to bring either pressure roller into a wire-feeding position by the forward feed cylinder H or by the reverse feed cylinder G. The wire is conducted from the reversible feed to the twister pinion gear box by a grooved bar 75.

The extra-tension device 15 comprises a lever 76 which is pivoted to the foundation plate. The lever is swung by the extra-tension cylinder C. The lever is in two parts which are pivoted together, and the upper part carries the fixed jaw 80 and the moving jaw 81 of a gripper which is operated by the action of a roller on the lower part. Extension of the piston rod of cylinder C first swings the lower part of the lever with respect to the upper part, which action causes roller 83 to ride over a cam surface 82 on moving jaw 81 and close the extra tension gripper. Continued extension of the piston rod of cylinder C then swings the lever as a whole to pull the wire.

55 The twister pinion gear box is topped by a nose plate 20. The twister pinion 20a is mounted just beneath the front edge of the nose plate on bored pivots 21, and is flanked by notched ejection bars 41 which slide backwards and forwards beneath the nose plate. The twister pinion is controlled by a twist cylinder D and an overtwist return cylinder B. The twist cylinder D drives the twister pinion on the upstroke only and rotates the twister pinion through three whole revolutions to apply the twist and a further fraction of a revolution to apply an overtwist. 60 The overtwist return cylinder B returns the twister pinion through the angle of overtwist. The mechanism for effecting these movements is not described because it forms no part of the present invention.

On the near side of the twister pinion, that is to say the side closer to the reversible feed, there is a holding gripper which consists of a body 47 and a head 49. The holding gripper is mounted for up-and-down movement

inside a tube 48 which carries at its upper end a knife 53. The tube is raised and lowered by a cam 53a which is followed by a roller 54 on the bottom of the tube. The holding gripper is raised and lowered by a lever 51 which is pivoted inside the box and extends forwards through slots in the tube, the gripper's body and the front of the gear box to the outside, where it is connected by a connecting rod 52 to the piston rod of air cylinder E. The head of the holding gripper is penetrated by a throughbore 50, which conducts the wire. The upper surface of the head co-operates with the nose plate in gripping the free end limb of the loop.

On the far side of the twister pinion there is a pseudo-gripper, so called, which consists of a body 57 and a head 58. The body is mounted for up-and-down movement in the box and is adapted to be raised and lowered by a lever 59 which is pivoted in the box and extends forward through slots in the pseudo-gripper's body and the front of the box to the outside, where it is connected by a connecting rod 60 to the piston rod of air cylinder F. The head of the pseudo-gripper and the nose plate together form a two-part guide structure which can be opened and closed. The top surface of the pseudo-gripper's head is crossed by a groove 61 which is open-ended and extends in the direction of wire feed. The underside of the nose plate is crossed by a similar groove 62 which is blocked at the far side and by a stop 65. The throughbore in the head of the holding gripper, the gap between the head of the holding gripper and the nose plate, the notches 41a in the upper edges of the ejection bars 41, the bores through the pivots 21, the slot in the twister pinion and the grooves in the pseudo-gripper and the nose plate constitute the flow path of the wire through the twister pinion gear box. During forward feed the holding gripper is open and the free end of the wire emerges from the bore 50 in the head of the holding gripper and passes a first time through the ejection bars and the twister pinion and into the groove 61 in the head of the pseudo-gripper, which at this time is closed. This groove 61 conducts the free end of the wire into the guide ring. After passing round the guide ring the free end re-enters the gear box through the gap between the head of the holding gripper and the nose plate and then passes a second time through the twister pinion. The upper groove 62 is positioned to receive the free end of the wire as it slides forward over the supply limb of the loop. The free end limb of the loop and the supply limb of the loop are thus in face-to-face relationship, one above the other, in the twister pinion. The flattened wire is a close sliding fit in the two grooves 61 and 62. Thus the two strands of wire in the pseudo-gripper are located against relative rotation without actually being gripped. The pseudo-gripper limits the twist on the far side of the twister pinion, as does the holding gripper on the near side.

There is an air duct 63 in the nose plate. This air duct opens into the upper groove 62 through a bleed port 63a. The operation of the air circuit is such that air is being discharged through this bleed port as the free end of the wire approaches its final position. The free end of the wire covers the bleed port and stops the discharge of air. The ensuing rise of pressure in the air duct is transmitted through a relay valve to a pilot valve which controls the last steps in the sequence of operations. One of these steps is termination of the forward feed. Another is the upward movement of the holding gripper.

In the embodiment described the pressure signal is a pressure rise and the free end of the wire itself acts as the obturator of the bleed port. However the bleed port may be controlled by its own obturator which is operated by the free end of the wire. For example the bleed port may be controlled by an obturator, such as a lever, which is dislodged by the free end of the wire, so as to open the bleed port. In this case the signal would be a pressure drop.

In this machine all the operations are carried out in an automatic sequence.

The air circuit is shown as it is at the beginning of a cycle. It includes three mechanically operated valves T, U and V and also a number of air-operated valves which are enclosed in a box 99. Compressed air is conducted from a source 100 through a filter 101, a pressure regulator 102 and a lubricator 103 to an emergency stop valve 104 which, in the position illustrated, conducts air to all the valve air inlets marked with a circle. The air outlets of these valves are marked with arrows. The circuit includes a manually-operated starting valve 105 and/or an automatic starting valve 106 which is operated by packages. On depressing the start button, a signal is sent from ring cylinder valve A_v through pressure drop valve Z₃ and the starting valve to pilot valve L. Pilot valve L reverses and sends its own air through valve A_v, overtwist return cylinder valve B_v and package-clamping cylinder valve J_v. These valves are reversed and thus the ring is opened, the piston rod of the overtwist return cylinder is retracted and the package-clamping cylinder J anchors the package by means of cross bar 92. When the ring is fully open, pressure drop valve Z₄ reverses and sends its own air through pilot valve P to reverse-feed cylinder valve G_v, which reverses against its spring. Thus, the reverse-feed pressure roller 71 comes down and the loop is contracted onto the package. Reverse feed continues until the tension in the loop equals the pull of the reverse feed rollers, whereupon these rollers climb the wire and shift the plate 68 on which they are mounted. This movement operates the trip valve V which sends its own air to pilot valve P. Pilot valve P reverses and diverts the signal from pressure drop valve Z₄ to extra-tension cylinder valve C_v. It also exhausts reverse-feed cylinder valve G_v which is reset by its spring. This stops the reverse feed.

The extra-tension cylinder valve C_v, now reversed, sends air of regulated pressure to the extra-tension cylinder C, which applies extra-tension to the loop round the package. Valve C_v also sends air through an adjustable flow regulator to the twist cylinder valve D_v. Valve D_v reverses and this reverses the air supply to twist cylinder D, which performs its upstroke. The upstroke rotates the twister pinion to apply a twist and an overtwist to the overlapping ends of the loop.

At the top of the upstroke of twist cylinder D, trip valve T is operated. This sends a signal to pilot valve M which reverses and diverts the signal from valve L to pilot valve N and cylinder valves J_v and D_v. It also removes the signal to cylinder valve B_v which is reset by its spring. Thus, simultaneously, cylinder J releases the package, the twist cylinder D commences its downstroke and overtwist return cylinder B returns the twister pinion through the angle of overtwist. The air supplied to pilot valve N passes to pseudo-gripper cylinder valve F_v and to holding gripper cylinder valve E_v. These valves reverse and the pseudo-gripper and the holding gripper go down.

It would appear impossible for the resetting signal from valve M to reset twist cylinder valve D_v, because the reversing signal from cylinder valve C_v has not been removed. However valve D_v is controlled by two pistons operating in separate chambers and air can be applied to both sides of each piston. The circuit is such that the resetting signal cancels the reversing signal on one of these pistons as well as applying its pressure to the other.

Towards the end of its downstroke, after ejection of the tie, the twist cylinder operates trip valve U which sends its own air to pilot valve N. This valve reverses and exhausts air from cylinder valve F_v, thus sending the pseudo-gripper up. Valve N also sends air to reset cylinder valve A_v, thus closing the ring. It also applies air to pressure drop valve Z₁ which cannot pass through until the twist cylinder has completed its downstroke. When this is so the pressure in the exhaust end of the twist cylinder 75 falls to a sufficiently low value to reset pressure drop valve

Z_1 and the air passes through to pressure drop valve Z_2 . Z_2 is reset when the pseudo-gripper is fully up and the air passes through to cylinder valve H_v .

Cylinder valve H_v reverses and sends its own air to forward feed cylinder H . The wire then begins to pass round the ring. At this moment air is bleeding through the bleed port 63 in the nose plate and also through a bleed port 108 which is controlled by an obturator 91 associated with the slack take-up device 18. When the forward feed comes into operation it first takes up the slack wire between itself and the supply reel. When this slack has been removed the slack take-up device is raised to close the bleed port 108. The pressure builds up in the bleed line and operates relay valve R which sends its own air to cylinder valve K_v . Cylinder valve K_v reverses with the result that the piston rod of cylinder K is extended. This motion separates two levers one of which carries a pawl and the other a brake pad. The brake pad comes off and the pawl kicks the reel to rotate it and pay off wire.

As shown in FIG. 1 the reel 17 carries a disc 107, the edge of which is engaged by a driving pawl 108 and a brake pad 109. The driving pawl is pivoted on driving lever 110 and the brake pad on brake lever 111. The driving lever is pivoted at one end to the shaft of the reel and at the other end to the rod of the cylinder K. The brake lever is pivoted at one end to the cylinder K and at the other end to a fixed pin which is eccentric to the shaft of the reel. Consequently, the arc of movement of the brake pad 109 intersects the edge of the disc. The pivot of the driving pawl is spaced from the edge of the disc by a distance less than the length of the pawl's tooth. Consequently, when the levers are separated, the brake pad comes off the disc and the pawl's tooth is jammed between its pivot and the edge of the disc by friction and so drives the disc. When the levers are moved towards one another, the pawl trails along the edge of the disc and the brake pad re-engages the edge of the disc.

When the wire is fully fed round the ring it covers the bleed port 63 in the nose plate. Pressure builds up in the bleed line and operates relay valve S, which sends a signal to reset pilot valve L. This valve sends air to reset cylinder valves E_v and H_v , thus disengaging the forward feed pressure roller 70 to terminate the forward feed and raising the holding gripper to anchor the free end limb of the wire. The cylinder valve E_v sends a signal to reset cylinder valve K_v . This results in the retraction of the piston rod of cylinder K and the application of the brake pad to the reel. This ends the cycle.

FIGS. 7 to 10 show a modified construction of the invention in which the bleed port is located in a block attached to the top of box 13 on the near side of the twister pinion. The block 130 has a through bore 131 which receives a spring seat 132 and a piston 133. The bore is intersected by the air duct 63. The piston is biased away from the air duct by a spring 134 into engagement with a lever 135, which is pivoted in a recess in the front face of the block. This recess is opposite the wire guide ring 11 which has a notch 136 to receive the tip of the lever. The free end of the wire engages the lever near the end of its travel through the groove 11a in the ring and thereby causes the piston to shut-off the bleed port 63a. FIGS. 9 and 10 show another construction in which the piston normally shuts off the bleed port and has a groove 137 which is brought into registry with the bleed port when the wire engages the lever. The distal end 138 of the air duct leads to atmosphere. The time delay of the air circuit is, of course, sufficient to allow the free end of the material to reach its final position before the forward feed is stopped.

An advantage of the construction shown in FIGS. 7 to 10 is that it enables a choice of pressure rise or pressure drop with a minimum of modification.

I claim:

1. For binding packages with a flexible metal binding material, a machine comprising:
means for feeding said material endwise;

a guide for receiving a free end of the material being fed and forming it in a loop with overlapping ends; means for tightening said loop around a package; a connecting device for joining the ends of the tightened loop;

pneumatic means for operating components of the machine in an automatic sequence which includes the loop-forming operation;

a controlling air circuit which includes an air duct and a bleed port to which the air duct leads;

a guide structure which the bleed port opens into and which is positioned to receive the free end of the material as it approaches its final position;

whereby the free end of the material itself acts as an obturator for said bleed port, and means in said air circuit responsive to pressure changes in said air duct for effecting a succeeding step in the sequence of operations.

2. A machine according to claim 1 wherein said guide structure comprises two parts of which one is movable and the meeting faces of which are formed with confronting grooves, one of said grooves being positioned when said guide structure is closed to conduct the material into the loop-forming guide and the other groove having a surface which contains said bleed port.

3. A machine according to claim 2 wherein said connecting device is a twister pinion and the binding material is flattened wire, and wherein said guide structure comprises a stationary upper part containing the groove with the bleed port and a movable lower part containing the other groove.

4. A machine according to claim 2 which further includes an air cylinder for opening and closing said guide structure and means in the controlling air circuit for causing said air cylinder to open the guide structure at the end of the twister action of the twister pinion and to close said guide structure after ejection of the tie.

5. For binding packages with flexible wire, a machine comprising:

forward and reverse feed means for feeding said wire endwise;

a guide for receiving a free end of the wire during forward feed and directing it to form a loop with overlapping ends;

a horizontal nose plate for supporting packages; a twister pinion mounted on said nose plate below the level of the upper surface thereof;

a holding gripper mounted between the forward and reverse feed means and said twister pinion, said holding gripper having a through passage for the wire passing from said forward feed means to said twister pinion said holding gripper co-operating with said nose plate to grip an adjacent portion of said loop; a guide structure on the other side of said twister pinion from said holding gripper, said guide structure comprising two parts one of which is movable to open and close said guide structure;

confronting grooves formed in the mating faces of said parts, one of said grooves being adapted to conduct the wire into the guide and the other groove being adapted to receive the free end of the wire as it approaches its final position;

an air duct terminating in a bleed port in said other groove;

said bleed port being positioned so as to be obturated by the free end of the wire;

means responsive to a pressure change in said air duct due to obturation of said bleed port for terminating the feeding action of the said feed means;

and air cylinders for powering and controlling components of the machine, said air cylinders operating in an automatic sequence.

6. A machine according to claim 5 wherein the wire is flattened and said guide structure comprises a portion of said nose plate and a vertically movable member, and

wherein said air duct is in said nose plate and terminates in a bleed port in the groove of said nose plate.

7. A machine according to claim 6 and further including pivoted levers for raising and lowering said holding gripper and said vertically movable member, and air cylinders for oscillating said levers. 5

8. A machine according to claim 7 wherein said forward and reverse feed means comprises:

two driving rollers geared together for rotation in opposite directions;
two pressure rollers;
a tilting holder in which said pressure rollers are mounted;
and two air cylinders for tilting said holder to bring either pressure roller into wire-feeding relationship 15 with its driving roller.

9. For binding packages with a flexible metal binding material a machine comprising:

means for feeding said material endwise;
a guide which receives a free end of the material being 20 fed and directs it to form a loop around a package;

means for tightening the loop;
a connecting device for joining the ends of the tightened 25 loop;

pneumatic means for operating components of the machine in an automatic sequence which includes the loop-forming operation;

a controlling air circuit which includes an air duct and a bleed port to which the air duct leads;

a member having a guide surface adjacent the final portion of the path of said free end, said guide surface including said bleed port, said bleed port being positioned so as to be closed by said free end to effect a pressure change in said duct;

and means in said air circuit responsive to a pressure 30 change in said air duct for effecting a succeeding step in the sequence of operations.

10. For binding packages with a flexible metal binding material, a machine comprising:

means for feeding said material endwise;
a guide which receives a free end of the material being 40 fed and directs it to form a loop around a package;

means for tightening the loop;
a connecting device for joining the ends of the tightened 45 loop;

10

25

30

35

40

45

pneumatic means for operating components of the machine in an automatic sequence which includes the loop forming operation;

a controlling air circuit which includes an air duct and a member having a bleed port to which the air duct leads;

an obturator controlling said bleed port; means for operating said obturator, said obturator-operating means comprising a movable member which extends into the path of the free end of the binding material so as to be displaceable by said free end to operate said obturator; and

means in said air circuit responsive to a pressure change in said air duct following operating of said obturator for effecting a succeeding step in the sequence of operations.

11. A machine according to claim 10 in which said member is formed with a bore into which said bleed port opens;

a piston in said bore controlling said bleed port; and in which said obturator operating means comprises a lever for operating said piston, said lever projecting into the path of said free end of the material near the final position thereof.

12. A machine according to claim 11 in which said piston normally closes said bleed port, said piston having a groove which is registerable with said bleed port to connect said bleed port to atmosphere.
